TOOL FOR CONNECTING SERVICE AND
MAIN LINES

Jasper Blackburn, Webster Groves, Mo.

Application July 15, 1938, Serial No. 219,367

12 Claims. (Cl. 81—53)

This invention relates to tools for the use of linemen in connecting or installing electric tap or service lines upon the main or pole to pole lines, or for disconnecting such service lines.

Such main lines are usually live and are also extended in somewhat unhandy or inaccessible locations, so that it would ordinarily be a matter of considerable hazard for a lineman to attempt to join a tap or service line to the live main line, without the use of some special tool for the purpose.

It is the prime purpose of the present invention therefore to provide a connector applying tool whereby a workman may conveniently and safely connect or disconnect a tap or service line to a live main line of an electrical system.

Another object is to provide a tool of the kind specified whereby a bifurcated bolt connector having a wire engaging slot and a nut threadable upon the bolt over the slot, may be conveniently held and manipulated for the purpose of joining a service line to a live main line, even though the latter be elevated or otherwise in a rather difficult or inaccessible position.

Still another object is to provide a tool of the kind referred to, the same including a rod having an insulated handle at one end, an adjustable chuck or tap holder at the opposite end, an elongated open frame slidably and rotatably mounted on the shank of the rod below the chuck, the said frame including off-set head and foot portions through the latter of which the shank of the rod has its slidable and rotatable mounting, means for releasably locking the chuck to the foot portion of the frame, and means upon the head portion for releasably engaging and holding a bifurcated and threaded wire connector with a service line supported in the slot thereof, whereby the connector and inserted service line may be positioned over the main line and the chuck or tap holder then manipulated for threading the tap up onto the bolt and clamping the service and main lines together, after which the tool may be released and removed from the work, and whereby the reverse of this operation may likewise be accomplished.

Still another object is to provide an insulated tool having means for releasably supporting a bifurcated and threaded bolt connector and service line inserted through the slot thereof and a nut supported in a spaced or open relation to the slotted end of the bolt for admitting a main line into said slot, and means for closing the nut over the slotted end and turning same up against the wires passed through the slot of the

bolt, for the purpose of connecting the wires, after which the tool may be removed from the work, the tool being adapted also for the reverse of the said operation, to-wit: the disconnecting of a service line from a main line. 5

With the foregoing objects and purposes in view, attention is directed to the accompanying drawings constituting a part of the specification, and wherein:

Figure 1 is a perspective view of the tool, the lower end of the handle being broken off.

Figure 2 is a frontal elevation of the tool, showing a hinged nut type of connector supported therein in open position and a service line extended through the slot of the connector, ready 15 for locating the connector and service line over the main line shown below the end of the connector.

Figure 3 is a view similar to Figure 2, showing the main line fully entered into the slot and the 20 nut or tap of the connector turned fully up for the purpose of clamping the service line and main line firmly together.

Figure 4 is a rear elevation of the tool alone.

Figure 5 is a longitudinal section through the 25 tool.

Figure 6 is an enlarged detail of the vertical clamp.

Figure 7 is a similarly enlarged detail of the horizontal clamp, showing however a modified 30 form of rotary cam in lieu of the lever cam of preceding form, for operating the clamp plates of the device.

Figure 8 is a detail of a unitary form of connector including a hingedly connected nut or 35 tap, same being the form exemplified in Figure 2 as supported upon the tool.

The tool comprising the subject matter of this invention includes an insulated handle 1 of suitable length and upon the outer end of which 40 is rotatably and slidably mounted an elongated open frame 2. This frame is formed with an open, oblong back portion 2a and head and foot portions or plates 2b—2c. A round hole or aperture 5 is formed through the foot plate 2c, and a ring or ferrule 6 is welded or otherwise secured in place over this hole at the outer face of the plate. The shank 1a of the handle 1 is rotatably and slidably mounted through the ferrule and aperture, the parts being nicely turned and 50 fitted so that the ferrule will serve to maintain the handle in an operative axial alignment with the frame 2 as a whole.

Upon the inner face of the foot plate and at opposite margins of the aperture 5, are rigidly 55

mounted by welding or the like, a pair of elongated stops 8 which are undercut or slotted longitudinally as shown at 9, at their oppositely turned ends, so that the slots open in an anti-clockwise direction with reference to a circle drawn through them concentrically with the aperture 5, and regarding the structure from above or at the inner side of the foot-plate 2c. This arrangement is for a purpose later to be pointed out.

10 An elongated chuck head 11 is rigidly mounted at the upper end of the shank 1a, transversely thereof, and this chuck head is formed at either end thereof with integral, inset and upstanding lugs 11a upon which are pivotally mounted the 15 chuck jaws 12. For this mounting the jaws are slotted out medially through their lower ends, as shown at 12a, so as to fit nicely yet freely over the lugs, to which they are then pivotally secured by means of pins 13. The jaws 12 are hollowed out longitudinally on their inner faces, as shown at 12b, while their outer extremities are formed angularly on a transverse plane, as shown at 12c, in order to facilitate the engagement of a nut or tap. Stops 12d are formed on the inner 20 faces of the jaws below the extremities, to limit the inward movement of a nut or tap between the jaws. An adjustment screw 15 is journaled through the bases of the jaws 12, the head 15a and nut 15b thereof being seated within sockets 30 or recesses 12e formed in the outer sides of the jaws, and an expansion coil spring 16 is then seated over this screw inside the jaws and is braced at its ends against the jaws so as normally tend to throw the jaws open or asunder. The 35 degree of separation or opening of the jaws may thus be readily regulated by means of this screw 15, for adapting the tool to taps of various size.

Thin and flat lugs 17 are extended at opposite sides of the opposite ends of the chuck head 11, and at the lower face thereof, in which location the lugs are adapted to engage the slots 9 of the stops 8, as the handle 1 and attached chuck head 11 are rotated in a clock-wise direction, regarding the assembly from above the foot plate 2c. By this operation the lugs 17 become wedged 45 firmly within the slots 9, and the handle and chuck are operatively locked to the frame 2, as is necessary in the operation of the tool, as will later appear.

50 From the under side of the inturned head portion 2b there is depended by means of screws 18—18a, an elongated, rectangular head block 19, cut out medially through its rear upper corner to provide a spring and lug recess 19a, and the head plate 2b is formed with a slot 2d opening down into this recess and extended diagonally towards a rear corner of the head plate. Also a pair of spaced bores 19b are formed perpendicularly through the head block 19, from top to bottom thereof, the said bores also piercing through the head plate 2b. Bolts 21 are slidably passed down through these bores, the lower ends of the bolts being rigidly anchored in a press plate 22, while the upper ends are threaded and passed 65 through a flat bridge piece 23, and nuts 21a turned onto the threaded ends above the bridge plate. The bolts 21 are reduced at their upper portions, whereby medial shoulders 21b are provided, and expansion coil springs 24 are seated over these upper ends of the bolts their ends being braced between the shoulders 21b and the under side of the head block 19, as clearly shown in Figure 6. Thus the normal action of the springs is to force the press plate 22 downward.

70 A slender latch lever 26 is pivoted at one end 75

26a to the screw 18 while the other end is extended across the top of the head plate 2b, the extremity of the lever being upturned to provide a finger piece 26b. A latch lug 26c extends upwardly from the lever 26, spaced inwardly from the pivoted end 26a and being so located and dimension as to pass in under the bridge piece 23 and between the upper ends of the bolts 21 when the bridge piece is raised upward from the plate 2b. Thus the lug 26c normally functions to maintain the bridge piece 23, as well as the press plate 22 in an elevated position, until these elements are released by pulling the latch 26 rearwardly and so withdrawing the lug 26c from under the bridge piece 23. When this is done the plate 22 15 of course flies downward to the extent of its limit of movement as determined by the length of the bolts 21. In order to facilitate the withdrawal of the latch lug 26c from beneath the bridge piece a lug 26d is depended from the lower 20 side of the lever 26 through the slot 2d of the plate 2b and down into the recess 19a of the head block 19. A retractile coil spring 29 is then stretched between this lug and the rear corner of the plate 2b in alignment with the slot 2d. 25 By this arrangement although the frictional hold of the bridge piece 23 under the action of the springs 24 upon the lug 26c will normally serve to hold same in place under the bridge piece, only a very slight pressure of the finger will suffice to 30 release same when desired.

A pair of wide thin clamping plates 31—31a are depended from the rear and frontal sides of the head block 19. These plates are cut out medially in a stepped manner so as to provide upper and 35 relatively narrow openings 32 and lower and relatively wide openings 32a, the openings being defined by the laterally aligned shoulders 32b, the latter being convexed outwardly as shown to form wire gripping jaws, while the pendant margins 33 40 of the lower and wider openings are flared apart as shown, to facilitate the operation of the tool as will appear in the description of the mode of operation. The upper opening 32 of the rear plate 31 extends somewhat higher than that of the frontal plate 31a, for a purpose later to appear. The rear plate 31 is rigidly secured by welding or otherwise to the head block, the method here shown being by means of screws 35, 45 while the frontal plate 31a is loosely mounted 50 thereon by the screws 35a passed freely through apertures 31b formed through the upper margin of this plate in a laterally spaced relation. Thus the frontal clamp plate may be moved towards or from the rear plate in the use of the tool and for 55 the purpose of engaging and gripping the wires, and as will be later more fully pointed out.

A flat leaf spring 37 is secured at its widened upper end to the upper margin of the back of the open frame 2 by means of spaced plates 38 60 secured by screws 39 over the lateral margins of the spring, the screws being seated into the back of the frame. The relatively narrow lower end of the spring 37 is thus free to pass forwardly between the side members of the open frame 2 as 65 clearly shown in Figure 5 at 37a, this end being convexed forwardly or outwardly as shown. This spring is primarily designed for use in a unitary type of bifurcated connector having a nut and washer assembly hingedly connected by one margin to one leg of the connector, and the spring would not be necessary except with this type, or one substantially similar. An operating aperture 37b is cut through the upper end of the leaf 70 spring, inside of the margins of the open back 2a 75

of the frame, and a box housing 40 is mounted over this aperture at the inner and forward face of the frame, there being a bore 40a formed through the forward wall of this housing. A bore 5 31c is formed medially through the upper margin of the plate 31a immediately over the upper opening 32 and in fore and aft alignment with the bore 40a of the housing 40, and an expansion coil spring 41 is then braced between the housing 40 10 and plate 31a, the ends of the spring being positioned over the said bores 31c and 40a, the normal action of which spring is to force the plates 31—31a asunder.

A bolt 42 is provided, the same having a bifurcated and elongated shank 43 rigidly joined to and extended axially from the rear end of the bolt, with the prongs or forks 43a thereof opening rearwardly in axial alignment with the bolt. A plate 44 of a width to fit between the plates 33, 15 and pierced with a pair of parallel slots 44a defined by a central rib 44b and thus adapted to slidably engage the said prongs 43a, is mounted by its slots over the said prongs of the bolt shank. A reversible cam and lever unit 45, having a 20 substantially rectangular cam head 45a and curved handle 45b is pivotally mounted between the prongs 43a of the shank 43 by means of a pin 45c passed through the outer ends of the prongs and the predetermined inner margin of the cam 25 head 45a when the handle 45b is turned downwardly, as shown in full lines in Figure 5. The adjacent outer or upper corner of the cam head is rounded off as shown at 45d to facilitate the 30 action of the head. With the elements thus assembled the bolt 42 is thrust from the rear of the frame, through the housing 40, bore 40a, spring 41 and bore 31c, and the plate 44 is seated between the spaced side plates 33.

A sleeve nut 47 with kerfed head 47a and having a heavy coil spring 48 mounted thereon, is 40 threadedly turned upon the forward protruding end of the bolt 42, the ends of the spring 48 being braced between the head 47a and the face of the 45 frontal clamping plate 31a, at the margin of the bore 31c. Thus by turning up or loosening the nut 47, the tension of the cam head 45a upon the rear clamp plate 31 may be regulated as desired.

It will be noted that with the cam unit 45 50 mounted as shown in Figure 5, with the handle 45b turned downwardly, an upward push upon this handle operates to press the rounded corner 45d of the cam head inwardly against the rib 44b of the slotted plate 44, thereby drawing the bolt 55 42 and frontal clamping plate 31a inwardly toward the rear plate 31, for the purpose of clamping together wires positioned between the jaws 32b. In this arrangement the handle 45b would be pulled inwardly or downwardly for the purpose of opening the jaws and releasing the wires by means of a cord 49 attached to and extended from the handle to the hand of the operator.

On the other hand, by merely reversing the 65 mounting of the cam and lever unit 45, by withdrawing the pin 45c and turning the handle 45b upwardly as indicated in dotted lines in Figure 5, and then reinserting the pin, it will be found that the clamping plates are then drawn together 70 by forcing the handle 45b downwardly, and that the plates are released or opened by pushing this handle upwardly, this being the reverse of the previous procedure. Both of these modes of operation are desirable in practice, the former procedure in the process of making connection of a

service line to a main line, and the latter procedure in the process of disconnecting a service line from the main line. The applying positioning of the elements is indicated in full lines in Figure 5, and the disconnecting positioning is 5 shown in dotted lines in the same figure.

Of course, the reversing of the mounting of the cam and lever unit in the form described requires a little time, and to avoid this a rotary cam unit might be employed, such as illustrated 10 in Figure 7. Here the housing 40 is dispensed with, as is also the bolt shank 43, the rear end of the bolt 42 being journaled straight through a circular cam element 50 having a beveled rear 15 face 50a, and being secured by screws 51 or otherwise to the rear face of the frame back 2a. A complementary cam element 52 is then rigidly anchored to the outer extended end of the bolt 42, this element having an inner beveled face 20 52a exactly equal and corresponding to the beveled face 50a of the element 50. A wheel or pulley 53 is rigidly mounted concentrically at the outer side of the cam element 52, and the cam elements are so closely associated that any rotation of the wheel 53 in either direction will operate to cause the beveled faces of the elements to slide or climb up one over the other, thus drawing the bolt 42 back rearwardly and contracting and drawing together the clamp plates 31—31a, similarly as already described. A cord 49a is given a couple of turns around the pulley 53, whereby the rotary cam may be rotated in either direction for opening or closing the plates 31—31a, in the use of the tool. 35

Now describing the use of the tool with the hinged nut type of connector 55 shown in Figure 8, the handle 1 and chuck head 11 are first rotated clock-wise for the purpose of wedging the lugs 17 within the slots 9, whereby the handle and frame 2 become stiffly and operatively aligned. The press plate 22 is then raised from the head plate 2b in manner already pointed out, and the latch lever 26 is pushed forwardly until the lug 26c passes under the bridge piece 23, whereby the press plate is held to its elevated position. The cam unit 45 is also released for allowing the plates 31—31a and the jaws 32b to open apart. The service line 56 is then inserted within the slot 55d of the connector, the connector 55 is next positioned within the lower openings of the plates 31—31a and back against the leaf spring 37 with the nut and washer unit 55c turned downward vertically or parallel with the longitudinal axis 55 of the connector, in which position this unit is held by the outward lateral pressure of the spring against the unit, pressing same against the leg of the connector to which it is hinged, as illustrated in Figure 8, and the cam unit 45 is operated by pushing up the handle 45b which forces the cam head 45a inwardly, thus drawing the jaws 32b inwardly and clamping the service line between them. Thus the entrance slot 55d is unobstructed for the entrance of the main line 57 65 as will be explained. The latch lever 26 is next pulled rearwardly for releasing the press plate 22, which then drops down upon the head 55b of the connector, forcing the head into firm contact with the service line held in the jaws 32b. Thus 70 the line of pressure of the plate 22 upon the head of the connector is perpendicular to the line of pressure of the jaws 32b upon the service line, and both the connector and line are firmly held in place on the tool. When the service line 56 is 75

inserted through the connector as above referred to, it is positioned up against the inner side of the head 55b and the arrangement of elements is such that the line will then normally extend out at both sides ready to be engaged by the jaws 32b as same are drawn together. The tool is then extended and the connector positioned astraddle the main line which passes up through the slot 55d against the service line and simultaneously 10 within the flared margins 33 of the plates 31—31a. Thus the service and main lines extend through the said flared margins 33 and are maintained in alignment thereby in the further operation of the tool, and kinking and twisting are prevented in the wires under the rotative torque of the tool in the operation of turning the nut upon the bolt connector.

The foregoing preliminaries being completed, the handle 1 of the tool is rotated in an anti-clockwise direction, always regarding the assembly from above the bottom or foot plate 2c, for the purpose of freeing the lugs 17 from the stops 8. The handle 1 is then pushed upwardly through the frame 2 and one of the opened jaws 25 12 is brought into contact with the nut and washer assembly 55c and incidentally the leaf spring 31 also. The lateral pressure of this spring is thus removed from bearing upon the nut and washer assembly, whereupon the latter 30 swings outwardly somewhat and permits the two jaws 12 to be worked thereunder for forcing same up against the end of the connector and ready to be turned thereupon. In other words and as will be seen from an inspection of the assembly 35 of Figure 8, the center of gravity of the nut and washer unit 55c would normally pull this unit angularly outward from the strictly vertical alignment shown in the drawing, and to which it is resiliently held by the pressure of the spring 37 against its upper margin. Thus 40 when the spring 37 is pushed back by the upward movement of the jaws 12, the unit 55c swings angularly out partially over the jaws 12, one of which may then be worked under the unit 45 to push it up into a horizontal position, after which the unit may be operatively engaged between the jaws for threading upon the connector. The handle of the tool is then rotated a turn or two in a clock-wise direction to enable 50 the jaws 12 to engage the nut and washer assembly and for aligning the leading threads of the latter with the corresponding threads of the bolt connector, after which by rotating the handle and jaws and the engaged nut in an anti-clockwise direction (always regarding the assembly from above), the nut and washer assembly 55 may be readily turned upon the bolt connector, until the former is pressed firmly up against the two wires 56—57, for locking them 60 together and completing the electrical connection. A pull upon the cord 49 then releases the cam lever unit 45, permitting the spring 41 to force the plates 31—31a asunder for releasing the tool from the joined wires and the connector. 65 This tool may then of course be readily withdrawn from the work.

For the purpose of reversing the described operation, as for disconnecting a service line from a main line, the positioning of the cam lever unit 70 45 would be reversed and the handle 45b would be turned upwardly as indicated in dotted lines in Figure 5. In this position the plates 31—31a and jaws 32b would stand open, and by means of the handle the jaws 32b and flared margins are 75 set over the joined service and main lines im-

mediately over the connector 55 and with the press plate 22 bearing on the head of the connector. The handle is then drawn downward or inward causing the plate 22 to move outwardly and bringing the jaws 32b into engagement with the service line 56 as same rests atop the main line 57. When the elements are thus properly located with respect to each other, a pull upon the cord 49 serves to clamp the jaws 32b upon the service line, after which the handle and chuck 11 may be manipulated to engage the nut and washer unit of the connector for unturning same from the connector and freeing the wires so that the service line may be withdrawn. An upward push by a pole or rod (not shown) against the lever handle 45b then serves to release the plates 31—31a and jaws 32b, and the service line may be pulled away and the tool removed from the work. In lieu of the cam and lever unit 45 just described and which requires reversing in position for installing or removing a service line upon a main line, the form of rotary cam unit shown in Figure 7 might be employed, same comprising the circular, beveled and complemental cam elements 50 and 52, 25 mounted and operated as already described.

While the foregoing description relates to a tool adapted for use with a bifurcated or slotted connector having a nut and washer unit hingedly connected to one of the legs thereof, and which 30 form of connector requires the use of the spring 37 or some equivalent means for maintaining the nut and washer unit in open relation to the connector to facilitate the entrance of the main line, it is to be understood that the same tool 35 may be used with other types of bifurcated and threaded connectors provided with taps or nuts to close over the slot of the bolt. In fact the tool may be used with the slotted form of bolt connector wherein the nut is designed for complete 40 removal and separation from the bolt for the purpose of admitting wires into the slot. In such case the nut would be separately positioned within the jaws of the chuck, ready for turning upon the connector after the latter with service line 45 inserted were properly locked upon the frame of the tool in the manner already described. It is obvious that in such use the spring 37 may be dispensed with entirely. Neither is the latch 26 an essential feature of the invention. The cardinal 50 features of the invention consist of a suitable handle with a frame slidably and rotatably mounted at one end and with releasable means for locking the two against relative rotation, there being clamping means on the frame for locking a bifurcated connector in substantial axial alignment with the handle the said clamping means being also releasable, the said clamping means including means for locking a service wire within the slot of the connector, means at the 55 end of the handle at the frame for supporting a tap in spaced axial alignment with the open end of the connector ready for turning thereupon after the connector and inserted service line have been hooked over the main line, and means upon the assembly for supporting same upon the main line with spaced bearings thereupon, for bracing the assembly and preventing the lines from turning or kinking under torque applied to the handle in the operation of turning the tap. 60

And while I have herein set forth and described a certain concrete embodiment of the invention, together with certain specific structural features thereof, it is understood that I may make such changes or alterations as may 75

be deemed expedient for the purpose of perfecting the tool and rendering same perhaps more practicable in use, not departing however from the essence of the invention as defined in the 5 appended claims.

I claim:

1. A tool for connecting or disconnecting a service line to a main line through use of a bifurcated or slotted bolt connector having a nut 10 threadable over the slot of the bolt for clamping the wires together, the tool comprising a handle, a frame rotatably and slidably mounted at one end of the handle, releasable means for locking the two stiffly together in utmost extended axial relation through relative rotation, releasable clamping means on the frame for supporting the connector with the service line inserted in the slot thereof in substantial alignment with the handle, and a chuck head and 15 jaws on the end of the handle for supporting a nut in operative and spaced alignment with the connector, whereby the main line may be entered into the slot of the connector against the service line and the handle then rotated to turn the nut upon the connector for clamping the wires together, the reverse operation of the tool 20 serving to disconnect the wires.

2. A tool for connecting or disconnecting a service and main line by use of a bifurcated or 25 slotted bolt connector having a nut threadable over the slot of the bolt for clamping the wires together, the tool comprising a handle, a frame rotatably and slidably mounted at one end of the handle, releasable means for locking the two 30 stiffly together in utmost extended axial relation by relative rotation to facilitate its use, releasable clamping means on the frame for supporting the service line with the connector positioned 35 thereafter, separate releasable clamping means on the frame for forcing the head of the connector down upon the service line, and adjustable means 40 on the end of the handle for supporting a nut in spaced and operative alignment with the open end of the connector, whereby the main line may 45 be entered into the slot of the connector against the service line and the handle then shoved inwardly and rotated to turn the nut upon the connector for clamping the wires together, the tool 50 being reversibly operated for disconnecting the wires.

3. In a tool of the kind described, a handle, a supporting frame slidably and rotatably mounted at one end of the handle, the frame having head and foot portions turned to one side, means supported from the head portion for releasably clamping a bifurcated wire connector with service line inserted in the slot thereof, in axial alignment with the handle, adjustable chuck jaws at the same end of the handle carrying the frame 55 for adjustably and releasably supporting a nut in spaced and operative alignment with the open end of the connector, latches operable through relative rotation of handle and frame for releasably locking same together in utmost axial extension, whereby the connector may be located over a main line, and then by rotation and inward movement of the handle the nut may be turned upon the connector for clamping the wires together, this operation being reversed for the 60 purpose of disconnecting the wires.

4. In a tool of the kind described, an elongate frame having head and foot portions turned right-angularly to one side thereof, the foot portion having a guide aperture therethrough, a 65 handle passed slidably and rotatably through

the aperture, an adjustable tap holder at the inner end of the handle and over-lying the margins of the ferrule, means dependent on relative rotation of handle and frame for releasably locking the two stiffly together with the handle drawn 5 fully outward, means depended inwardly from the head portion for releasably clamping a service line at two spaced points with a bifurcated bolt connector suspended thereon between these 10 points in operative axial alignment with the handle and tap holder, separate releasable means for pressing the head of the connector upon the inserted service line, and means supported on the frame outwardly of and in alignment with the service line clamping means, for engaging a main 15 line for steadyng the tool in use.

5. In a tool of the kind described, a handle, an elongate frame slidably and rotatably mounted at an end of the handle, means at the same end of the handle for releasably holding a tap, means 20 functioning through rotation of the handle relative to the frame for releasably locking the two together, spaced service-wire clamping jaws extended inwardly at the opposite end of the frame, a spring set draw-bolt passed through the jaws 25 and frame, means at the back of the frame engaging the protruded end of the bolt for drawing same back to close the jaws upon an inserted service line, and means for forcing down the head of a bifurcated bolt connector upon the service line 30 whereon it is suspended between the said wire 35 clamping jaws.

6. In a structure as defined in claim 5, means supported on the frame for engaging a main line at lateral points for steadyng to tool in operation. 35

7. In a tool of the kind described in claim 5, a leaf spring depended from the back of the frame, its lower end being extended inwardly and adapted to bear upon the hingedly connected tap of a unitary form of connector for holding same 40 open for reception of a main line.

8. In a tool of the kind described, a handle, an elongated frame having inturned ends the same being rotatably and slidably mounted through one end upon an end of the handle, a tap-holding chuck-head at the end of the handle within the frame, co-operating elements on the chuck-head and frame for releasably locking by relative rotation the handle and frame together in out-most extended, axial relation, 50 pairs of superposed, laterally spaced, oppositely aligned and adjustable tap-wire gripping jaws depended from the opposite inturned end of the frame, releasable means for closing these jaws upon an inserted tap-wire, and releasable means 55 for supporting a bifurcated bolt connector astraddle the tap-wire between the said jaws, for locating same by means of the handle, upon a main wire, whereby a tap releasably held by the chuck in alignment below may be raised and 60 mounted upon the connector for joining the tap and main lines, and the tool then removed, and whereby an installed connector may be removed 65 from the wires by reversing the operation.

9. In a tool of the kind described, a handle, 65 an elongate frame rotatably and slidably mounted at one side of the frame to slide longitudinally there along, a tap-holder at the end of the handle at the frame adapted to releasably hold a tap, co-operating elements on the frame and tap holder for releasably locking by relative rotation the handle and frame together in utmost extended axial relation, pairs of superposed, laterally spaced jaws depended from the opposite end of the frame towards the tap holder, 70 75

releasable means for closing the jaws upon an inserted tap-wire, and releasable means for supporting a bifurcated bolt connector astraddle the tap-wire between the jaws in operative alignment 5 with a tap releasably held by the tap holder, whereby the tap line may be applied to a main line by setting the connector also astraddle the main line, releasing the handle to slide the tap holder to the connector and turn the tap onto 10 same, or whereby the lines may be disconnected by reverse operation.

10. In a structure as defined in claim 9, spaced and flared main line guides supported upon the frame outwardly of and in alignment with the 15 inner tap-wire jaws, for supporting the elements engaged against torque.

11. In the structure as defined in claim 9, the said releasable means for supporting the con-

nectors astraddle the tap-wire comprising a spring-set press-plate movable mounted on the frame and adapted releasably to press down upon the head of the connector for forcing it to the wire. 5

12. In a tool of the kind described, a handle, a frame slidably mounted at one end of the handle, means for releasably locking the frame and handle fixedly together, spaced service-wire 10 clamping jaws extended inwardly at the opposite end of the frame, a draw-bolt passed slidably through the jaws and frame, means on the frame for forcing the bolt rearward for closing the jaws upon an inserted service line, and means for forcing down the head of a bifurcated 15 bolt connector upon the service line whereon it is suspended between said wire clamping jaws.

JASPER BLACKBURN.
